CLAIM

The ornamental design for a solar sensor light with clip, as shown and described.

DESCRIPTION

FIG. 1 is a front elevational view of a solar sensor light with clip showing my new design;
FIG. 2 is a rear elevational view thereof;
FIG. 3 is an enlarged left side view thereof;
FIG. 4 is an enlarged right side view thereof;
FIG. 5 is a top plan view thereof;
FIG. 6 is a bottom plan view thereof;
FIG. 7 is a bottom perspective view thereof;
FIG. 8 is a top perspective view thereof;
FIG. 9 is another bottom perspective view thereof;
FIG. 10 is an exploded view thereof; and,
FIG. 11 is another exploded view thereof, in which the top portion is shown rotated.
